UNITED STATES PATENT OFFICE

FRANK C. MORROW, OF WELLSTON, OHIO

CONVEYER GUIDE

Application filed October 25, 1930. Serial No. 491,296.

This invention relates to endless conveyors of that type generally used for retarding the movement of coal from a mine opening to a tipple located at a considerable distance 5 therebelow.

In the mountainous districts the coal is often found at an elevation several hundred feet above any point where it is possible to build a railroad. Under these conditions it 10 has been the practice to provide a trough leading from the mine opening downwardly to a point where a tipple has been erected. In order to prevent the mined coal from traveling down this trough at too great a speed, 15 a cable conveyer having regularly spaced disks has been employed for retarding the flow of the material. The lower strand of the cable with disks thereon travels in the direction in which the coal is moving, sheaves being provided at the ends of the trough for the 20 purpose of properly guiding the conveyer and for transmitting motion thereto. The weight of the moving coal frequently provides almost enough power to actuate the retarding cable provided the trough is straight 25 from end to end or has a concaved portion with a radius of not less than one thousand feet. However, in those localities where it is necessary to use a trough having one or more 30 humps due to the fact that a portion of the trough is inclined less than another portion therebelow the resistance offered to the upward travel of the upper strand of the cable due to friction at the humps has been so great 35 as to require the expenditure of much more power than is desirable in order to operate the conveyer.

An object of the present invention is to 40 provide a novel form of supporting mechanism for the upper strand of a cable conveyer at those places where said strand is compelled to travel over humps.

Another object is to provide a mechanism 45 of this character which will be properly geared at all times to the conveyer so that there will be no danger of the said mechanism getting out of properly timed relation with the conveyer and causing breakage or other injury to the apparatus.

50 With the foregoing and other objects in

view which will appear as the description proceeds, the invention resides in the combination and arrangement of parts and in the details of construction hereinafter described and claimed, it being understood that changes 55 in the precise embodiment of the invention herein disclosed, may be made within the scope of what is claimed, without departing from the spirit of the invention.

In the accompanying drawings, the preferred form of the invention has been shown.

In said drawings:

Figure 1 is a side elevation more or less in diagram showing troughs equipped with a cable conveyer guided at a hump by the mechanism constituting the present invention. 65

Figure 2 is an enlarged side elevation of the guiding mechanism showing a portion of the upper strand of a conveyer in engagement therewith. 70

Figure 3 is a plan view of the structure shown in Figure 2.

Figure 4 is an enlarged section on line 4-4, Figure 1.

Figure 5 is a vertical transverse section 75 through the conveyer at an intermediate point such as indicated, for example, by the line 5-5 in Figure 1, a portion of the supporting structure and housing of the troughs and conveyer being shown.

Referring to the figures by characters of reference, 1 designates a frame work of the usual or any preferred construction erected between the mine outlet and a tipple therebelow for the purpose of supporting a continuous lower trough 2 and an upper or guiding trough 3. Sheaves 4 and 5 are provided adjacent to the upper and lower ends of the troughs and have peripheral recesses 6 which are regularly spaced apart for the reception 80 of disks 7.

The disks 7 are secured at regular intervals to an endless cable 8 the lower strand of which travels downwardly in the trough 2 while the upper strand travels upwardly in the trough 3. Any suitable power mechanism, indicated generally at 9, can be used for driving the sheave 4 so that the lower strand of the cable conveyer will move within the trough 2 at a predetermined speed. Thus coal delivered 100

into the trough 2 at its upper end can only move downwardly therein at the same speed as the conveyer because the disks will act as retarders.

5 It can be readily seen that where the troughs are straight from end to end very little power will be required to actuate the conveyer. However, when the troughs are necessarily provided with humps at one or more points, the upper strand of the conveyer while traveling upwardly over the humps will produce a frictional resistance of such a high degree as to require the use of considerable added power in order to operate the conveyer. 10 Furthermore excessive wear upon the parts will be produced at the humps.

Obviously a sheave such as shown, for example, at 4 and 5 could not be used because, in order to prevent the cable from slipping on the periphery of the sheave, it is necessary that one of the disks be at all times in engagement with the sheave. Unless this uninterrupted engagement is provided, the cable would slip on the sheave during the intervals when the disks are out of engagement therewith and, as a result, the disks would not enter the peripheral recesses provided for them. Obviously this would result in breakage or other injury to the apparatus.

15 In order to properly guide the upper strand of the conveyer over a hump and at the same time prevent slippage of the conveyer relative to its guiding means, a special form of apparatus has been devised. This includes a series of sheaves 10 the peripheral portions of which are so shaped as to embrace and properly engage the upper strand of the conveyer cable where it passes over the hump. These sheaves are located in a break or gap provided in trough 3 at the hump as shown at 20 11 and formed in the periphery of each sheave are gaps 12 which are regularly spaced so as to receive the disks 7 as the cable 8 moves upwardly.

25 The shafts 13 of the sheaves can be journaled in a suitable frame 14 and each of them is provided with a gear 15. Intermediate gears 16 are supported between the gears 15 and mesh with them so that when power is applied to any one of the gears 15 the remaining gears 15 will be rotated in unison therewith.

The gaps 12 in the several sheaves are so positioned that during the movement of the cable 8 upwardly over the hump one of the disks on the cable will always be in engagement with the front or advancing wall of one of the gaps thereby to exert a thrust against one of the sheaves and set up a simultaneous rotation of all of the sheaves. As one disk passes out of contact with one wall of a gap another disk is moving into contact with one wall of another gap in one of the other sheaves.

30 The foregoing operation will be apparent

by referring to Figure 2 wherein disk *a* is thrusting against one wall of a gap in the middle sheave while disk *b* is moving to a position where it will thrust against one wall of a gap in one end of a sheave. At the same time disk *c* has been released and is moving outwardly from the gap in which it had been exerting a thrust. As the various disks are brought to position at the hump they will all be brought successively into operative engagement with a wall of a gap in one of the series of sheaves so that it is impossible for the conveyer to slip on the sheaves. Instead, the conveyer is constantly geared to the sheaves and accurate entry of the disks into the gaps is insured.

What is claimed is:

1. The combination with an endless cable conveyer having regularly spaced disks, of means for holding in an elevated position an intermediate portion of one strand of the conveyer, said means including alining sheaves having peripheral disk receiving gaps and driving connections between the sheaves spaced from and out of engagement with the conveyer, said disks and sheaves being movable in properly timed relation to maintain a constantly geared connection between the conveyer disks and the sheaves.

2. The combination with an endless cable conveyer having regularly spaced disks fixed thereto, of means for supporting and guiding an intermediate portion of one of the strands of the conveyer, said means including a group of separate conveyer engaging sheaves each having peripheral gaps, and driving connections between the sheaves and spaced from the conveyer for insuring rotation thereof in unison, said disks cooperating with the walls of the gaps to maintain a constant driving connection between the conveyer and the sheaves.

3. The combination with an endless cable conveyer having regularly spaced disks, of means for supporting and guiding an intermediate portion of one of the strands of the conveyer, said means including a group of separate sheaves having peripheral gaps for the reception of the disks, and gears out of the path of the conveyer for transmitting motion between the sheaves to rotate the sheaves simultaneously and at the same speed, the disks cooperating with the walls of the gaps to maintain a constant driving connection between the conveyer and the sheaves.

In testimony that I claim the foregoing as my own, I have hereto affixed my signature.

FRANK C. MORROW.
